UNITED STATES PATENT OFFICE.

CHARLES HOLSINGER, OF KENDALLVILLE, INDIANA.

METALLIC FENCEPOST.

1,407,540.

Specification of Letters Patent. Patented Feb. 21, 1922.

Application filed July 12, 1919. Serial No. 310,295.

To all whom it may concern:

Be it known that I, CHARLES HOLSINGER, citizen of the United States, residing at Kendallville, in the county of Noble and 5 State of Indiana, have invented certain new and useful Improvements in Metallic Fenceposts, of which the following is a specification.

This invention relates to an improved 10 fencepost and has as one of its principal objects to provide a metallic post which may be economically produced and which will be adapted for general use in building fences.

The invention has as a further object to 15 provide a fencepost equipped with anchoring means of such nature that, in use, the post will be rigidly supported in the ground, thus minimizing the tendency of a fence carried by a line of the posts to sag.

20 A further object of the invention is to provide a post which, with its anchoring means, may be readily driven into the ground.

And the invention has as a still further 25 object to provide a metallic post which may be readily employed in lieu of ordinary wooden fenceposts and will thus fulfil a particular need in any locality where wooden posts are not available.

Other and incidental objects will appear 30 hereinafter. In the drawings:

Figure 1 is a fragmentary perspective view showing a section of fence employing posts of the type of the present invention,

Figure 2 is a front elevation showing the 35 post in detail,

Figure 3 is a transverse sectional view taken on the line 3—3 of Figure 2,

Figure 4 is a fragmentary perspective view 40 showing the manner in which the post is sharpened at its lower end so that the post may be readily driven into the ground,

Figure 5 is a front elevation on an enlarged scale, this view showing a modification of the invention, and

Figure 6 is a rear perspective view of the 45 modified form of post.

In forming my improved post, I employ a face plate 10 having a flat front face and which is somewhat tapered in thickness 50 toward its side edges. Extending at right angles from the face plate at its rear side is a medial reinforcing plate 11 integral with the face plate, the post thus being substantially T-shaped in cross section. The 55 reinforcing plate 11 is co-extensive with the length of the face plate and like the face

plate is somewhat tapered in thickness toward its outer side edge. Formed in the side flanges of the face plate or those portions of the plate lying at opposite sides of the plane of the reinforcing plate 11, is a plurality of vertically spaced openings 12 arranged adjacent the outer edges of said flanges. As particularly brought out in Figure 2, the openings in one flange are staggered with respect to those in the other. Adjacent the lower end of the face plate the side flanges thereof are, as particularly shown in Figure 4, cut away to provide beveled edges 13 converging to the plane of the lower end of the reinforcing plate 11 while the reinforcing plate is, in turn, provided adjacent its lower end with beveled side faces 14. The post is thus provided at its lower end with a pointed or piercing terminal. Riveted or otherwise secured to the base portion of the post is a transversely disposed anchoring plate 15 lying flat against the outer face of the plate 10 and extending at substantially right angles thereto.

As will now be readily understood in view of the preceding description, the post with its anchoring plate 15 may, as shown in Figure 2, be driven into the ground and, in use, the base portion of the post will be sunk a distance sufficient to well embed the anchoring plate. It is to be noted that the anchoring plate is flat on both sides throughout its area so that there are no laterally projecting portions to resist the downward progress of the anchoring plate into the earth and inasmuch as the plate is thin so as to avoid unnecessary weight and cost it will make such a narrow fissure in the ground that the opposing walls of the fissure will readily close over the plate as it is driven downward. The plate will thus be firmly anchored in the ground without undue disturbance of the soil. Thus, the anchoring plate not only serves to retard withdrawal of the post but will also brace the post laterally. In Figure 1, I have shown a pair of the improved posts in connection with a section of fence. As illustrated in this figure, woven wire 16 may first be secured to the posts so as to closely approach the ground when spaced top strands 17 of barbed wire may then be secured to the upper end portions of the posts above the woven wire. A particularly efficient fence is thus provided and, as will be observed, the posts are arranged so that the woven wire

and barbed wire will lie against the outer faces of the face plates 10 of the posts. Consequently, tie wires 18 may be readily inserted through the openings 12 in the posts 5 for rigidly securing the fence wires in position thereon.

In Figures 5 and 6 of the drawings, I have illustrated a slight modification of the invention. In this modification the face plate 10 of the post is indicated at 10' and the reinforcing plate at 11', these elements being similar to corresponding elements of the preferred construction. Also as in the preferred construction, the base portion of the 15 post of this modification is provided with a transverse anchoring plate 15' corresponding to the anchoring plate 15. Riveted or otherwise secured to the post at a point above the anchoring plate 15' is a supplemental 20 anchoring plate 19. This anchoring plate may be of less width and length than the main anchoring plate 15' of the post and is arranged to seat flat against the outer face of the plate 10' extending in substantially parallel relation to the main anchoring plate. As will be observed, the plate 19 is so disposed with respect to the main anchoring plate that when the post is embedded 25 in the ground, the plate 19 will be spaced above the ground surface. Formed in the end portions of said plate at its upper edge are outwardly inclined notches 20 and detachably engaged in these notches are the loops formed upon the upper sections of tie 30 rods 21. The lower sections of said rods are suitably engaged with anchoring stakes 22 driven into the ground at points spaced upon opposite sides of the post and preferably lying in the plane of the plate 19. The 35 anchoring stakes may be of any approved character and should, as shown in the drawings, be inclined away from the post. Adjustably connecting the confronting ends of the upper and lower sections of the tie rods 40 respectively are turn buckles 23. Thus, after the post has been set and the stakes 22 have been driven into the ground, the tie rods may be arranged in position extending between the plate 19 and the stakes when by 45 properly adjusting the turn buckles 23 the tie rods may be tensioned. As will be seen, these tie rods will serve a two-fold function in that they will not only act in conjunction with the main anchoring plate 15' for preventing lifting of the post by fence wires 50 connected thereto but will also brace the upper exposed portion of the post against lateral movement and strain in the plane of

the fence wires. Owing to the uneven contour of the ground it very often happens that one or more posts are located in a hollow. Consequently, when the fence wires 60 are stretched, the tension upon the fence wires will tend to lift the posts in the hollow and will also exert a side strain upon such posts in the direction of the fence line. As will be seen, this modified construction 65 provides an arrangement whereby, under the conditions indicated, the posts will be effectively secured to resist the tension of the fence line thereon. It will, of course, be readily noted that the downwardly and 70 outwardly inclined disposition of the notches will cause the outer walls thereof to slightly overhang the ends of the tie rods so that they will not be apt to be dislodged in the event that the tension thereof should be reduced through accident or some slight yielding of the anchoring stakes. Moreover, the 75 notches permit the tie rods to be readily engaged in the anchoring plate without any necessity for threading or worming the ends 80 of the rods through the plates. To engage the rods with the anchoring plate, it is necessary merely to slip the end of the rod over the upper outer corner of the anchoring plate and bring the end of the rod into the 85 notch.

Having thus described the invention, what is claimed as new is:

The combination of a fence post comprising a body T-shaped in cross section with the head of the T parallel with the line of the fence, means for securing fence wires thereto, a flat anchoring member set on edge and secured against the head of the T-shaped body with its ends projecting beyond the 90 edges of said head, a supplemental anchoring member secured against the head of the T-shaped body above the first-mentioned anchoring member and provided with outwardly and downwardly inclined notches in 95 its upper edge near its ends, anchoring stakes set at opposite sides of the body, said stakes and the supplemental anchoring member being in a plane parallel with the face of the T-shaped body, tie rods engaged at 100 their upper ends in the notches in the supplemental anchoring member and at their lower ends around the heads of the anchoring stakes, and tension devices interposed in 105 said tie rods intermediate the ends thereof. 110

In testimony whereof I affix my signature.

CHARLES HOLSINGER. [L. s.]
